United States Patent Office.

GEORGE W. CASILEAR, OF WASHINGTON, DISTRICT OF COLUMBIA.

Letters Patent No. 99,757, dated February 15, 1870.

IMPROVEMENT IN BANK NOTES, BONDS, REVENUE STAMPS, &c.

The Schedule referred to in these Letters Patent and making part of the same.

To all whom it may concern:

Be it known that I, GEORGE W. CASILEAR, of Washington, District of Columbia, have invented a new and useful Improvement to be applied to Revenue Stamps, Bank Notes, Checks, Bonds, or other engraved or printed securities or valuable papers, to prevent fraudulent tampering with the written signatures, sums, values, or other written matter making a part of the same; and

My improvement consists in ruling, in an ornamental design, ground tint over the otherwise blank portion of the paper reserved for and intended to receive such writing, consisting of lines, preferably in the form of waved, crossed, and interlaced work, or such other appropriate design as may be preferred, in the manner of ordinary paper-ruling, using for that purpose liquid ink similar in its nature and chemical properties to that of the ordinary ruling-ink, which is to be subsequently used in writing over and upon the signatures or other matter giving value to the paper intended to be protected by this device; the only difference between the two inks being that of color and tint, the ink used for the ground being of a much fainter or lighter tint than the writing ink, those colors being preferably selected which render copying by photography impossible; such a combination being that of the deep yellow and light bluish hues, the one possessing very slight, and the other very powerful actinic properties, which render these tints, although so graded as to appear to the eye as of about the same general depth of color, yet when photographed, to present a violent contrast in depth, the yellow appearing perfectly black, and the blue almost white, and at the same time entirely lacking any distinction of hue.

In the specimen drawings accompanying this application the improvement is shown as applied to internal revenue stamps.

The position occupied by the ground-tint ruling, marked A, being that intended for the assessor's name, date, cancellation, &c.

The manner of adapting the invention to bank notes, and other papers of value is so obvious as to require no further specification.

The security arising from the employment of this device consists in the condition that the ground-tint is ruled in with liquid ink of the same chemical and mechanical nature as the ink used in subsequently

writing over it, which renders any attempt to obliterate or remove the latter by means of solvents, acids, chemicals, or any means whatever, whether chemical or mechanical, equally effective in attacking and removing the ground-tint itself, and thus frustrating the attempt and furnishing evidence of the fraud, which, combined with the actinic features above explained, renders this the best protection for paper composed of combined printing and writing against a certain species of easy and therefore widely practiced fraud, yet devised.

In using the ordinary printed ground-tints heretofore employed upon checks, notes, and particularly upon stamps, in which the ground is printed in permanent oil colors, it is found to be a matter of comparative ease to discharge the written portion without injury to the ground-tint, and such stamps, &c., being used again and again for new signatures, cancellations, &c., frauds are thereby sustained by the revenue to the extent of many millions of dollars.

One great practical advantage of this invention is that the ruling can all be done expeditiously, and at a merely nominal cost, by employing the ordinary ruling-machine to rule in the lines composing this ground.

A preferable form for each line is that in which the different colors employed are curved and interwoven together by one simultaneous and automatic operation, which is accomplished by means of an improved attachment to ruling machines patented by me by patent bearing the same date herewith.

Having thus described my invention,

What I claim as new, and desire to secure by Letters Patent, is—

As an improvement in bank notes, or other similar papers representing value, leaving the spaces for signatures or other written portions entirely blank or free from engraving, and subsequently ruling in by machine over such blank spaces a lace-work ground design, in fluid inks of opposite actinic powers, to be subsequently written over with ordinary writing-fluid, substantially as and for the purpose set forth.

GEO. W. CASILEAR.
